UNITED STATES PATENT OFFICE.

SIDNEY A. KELLER, OF NEW YORK, N. Y., ASSIGNOR TO AMERICAN HARDWARE CORPORATION, OF NEW BRITAIN, CONNECTICUT, A CORPORATION OF CONNECTICUT.

DESIGN FOR AN ESCUTCHEON.

44,445.

Specification for Design.

Patented Aug. 5, 1913.

Application filed May 23, 1913. Serial No. 769,497. Term of patent 7 years.

To all whom it may concern:

Be it known that I, SIDNEY A. KELLER, a citizen of the United States, and a resident of New York, borough of Manhattan, in the county of New York and State of New York, have invented a certain new, original, and ornamental Design for an Escutcheon, of which the following is a specification.

In the accompanying drawing, Figure 1

is a plan view of an escutcheon having my design applied thereto; and Fig. 2 a cross-sectional view thereof.

I claim:

The ornamental design for an escutcheon, as shown.

SIDNEY A. KELLER.

Witnesses:

L. AUSTIE,

T. DREYFUSS.
